HIGH TEMPERATURE LAMP

John W. Marden, East Orange, N. J., assignor to
 Westinghouse Electric & Manufacturing Company,
 East Pittsburgh, Pa., a corporation of
 Pennsylvania

Application February 7, 1942, Serial No. 429,844

9 Claims. (Cl. 176—122)

This invention relates to electric lamps and, more particularly, to such adapted to operate at very high temperatures by virtue of being formed, at least in part, of material which will stand exceeding high temperatures without fusing.

The principal object of my invention, generally considered, is the production of electric lamps formed, at least in part of material, more refractory than quartz and having the ability to efficiently transmit desired radiations.

Another object of my invention is the production of electric discharge lamps adapted to operate with more intense arcs than have heretofore been possible in quartz, by virtue of being formed, at least in part, of a material such as fused magnesia or alumina which has a higher melting point than quartz.

A further object of my invention is the production of electric discharge lamps consisting of envelopes of quartz or other suitable material with refractory, light-transmitting means between the electrodes, such as a liner formed of magnesia, for restricting the arc therebetween without at the same time melting or otherwise deteriorating.

A still further object of my invention is the provision of discharge lamps each having a baffle or baffles of refractory material, such as magnesium oxide, to thereby restrict and provide a more intense arc than is possible with the use of less refractory material, said lamps being adapted to produce radiations, not only from the discharge but from portions of the baffle or baffles brought to incandescence.

An additional object of my invention is the provision of discharge lamps in which the intermediate portions are formed of refractory material such as fused, transparent magnesia, in the form of tubes, the ends of said tubes being closed by the use of graded seals through which leads for the associated electrodes pass, said magnesia tubes desirably providing a constricted path for the discharge to thereby increase the intensity thereof to the desired point.

Other objects and advantages of the invention relating to the particular arrangement and construction of various parts, will become apparent as the description proceeds.

Referring to the drawing,

Fig. 1 is an axial sectional view of an electric discharge lamp formed with an envelope of quartz having a liner of magnesium oxide, or other similar refractory material, for restricting the discharge.

Fig. 2 is a traverse sectional view on the line 55 vention illustrated in Fig. 3, the construction

II—II of Fig. 1 in the direction of the arrows.

Fig. 3 is a view corresponding to Fig. 1 showing a modification in which the envelope of the lamp is formed of quartz and a pair of baffles of refractory material are provided, one adjacent each electrode.

Fig. 4 is a view corresponding to Fig. 3 but showing another form of my invention in which the entire central portion of the envelope is formed of refractory material such as fused magnesia and the end portions are graded therefrom to receive the lead-in conductors for the electrodes.

Fig. 5 is a view corresponding to Fig. 3 but showing another form of my invention in which only one baffle is used and the envelope is short so as to provide a point source of light.

Referring to the drawing in detail, and first considering the embodiment of my invention illustrated in Figs. 1 and 2, there is shown a discharge lamp 11 consisting of an envelope 12 of quartz. The envelope is elongated and an intermediate portion thereof is partly closed by a liner 13 formed of material which efficiently transmits the desired radiations, but which is more refractory, that is, has a considerably higher melting point than the material of the envelope 12. The walls of the liner are, therefore, preferably thicker than those of the envelope. One of the most suitable materials for this purpose is pure fused, light-transmitting magnesia, which has a melting point of about 2800° C. Such material is a good transmitter, not only of visible light, but also of infra-red and ultra-violet radiations. At the same time it melts at such a high temperature that it may be brought to incandescence and augment the light by the discharge without deterioration or change in shape. It may be finished, after rough forming from the fused condition, by machinery with specially hardened tools known in the art.

The lamp 11 may otherwise be constructed like a high intensity mercury discharge lamp, a globule of mercury being indicated at 14. It is not necessary to have the entire envelope formed of magnesia because the hottest part will be where the liner 13 is positioned, and it is thereby possible to seal the lead-in conductors 15 and 16, having proper sealing characteristics, to the ends of the quartz envelope 12 for the support of the associated electrodes 17 and 18. The electrodes may be formed of tungsten or other similar material.

Referring now to the embodiment of my invention illustrated in Fig. 3, the construction

there disclosed is similar to that in Figs. 1 and 2, except that instead of a liner 13, the quartz envelope 12^a of the lamp 11^a has a pair of baffles 19 and 21 formed of pure fused, light-transmitting, magnesia, like the liner 13 of the preceding embodiment, but shortened axially of the envelope and provided with restricted apertures 22 and 23 therethrough for permitting a discharge of small diameter to pass between the electrodes 17^a and 18^a. Otherwise the construction may be identical with that of Figs. 1 and 2.

Referring now to the embodiment of my invention illustrated in Fig. 4, there is shown a lamp 11^b having an envelope 12^b, the central or intermediate portion of which consists of a tube 24 having a small bore 25 and formed of pure fused, light-transmitting, magnesia like the liner 13 of Fig. 1. At the ends of this member 24, quartz chambers 26 and 27 are provided for the associated electrodes 17^b and 18^b, the lead-in conductors 15^b and 16^b for said electrodes passing through the outer ends of said chambers 26 and 27.

In order to make it possible to seal lead-in conductors of tungsten or other suitable lead material through the outer ends of said chambers, the lead-in receiving portions of the envelope 12^b are connected to the magnesia intermediate part 24 by graded or stepped seals, that is, the composition of the material of the chambers 26 and 27 may vary in expansion between the seal material through which the leads pass and magnesia, so that the segments 28 and 29 are adapted to seal to the ends of the magnesia tube 24 without breaking, while the extreme portions 31 and 32 are adapted to permit the passage of the lead-in conductors 15^b and 16^b without the formation of cracks. Otherwise, the construction of the lamp may correspond with that of known high-intensity mercury discharge lamps.

Referring now to the embodiment of my invention illustrated in Fig. 5, a lamp 11^c is here disclosed, which may be identical with the lamp 11 of the first embodiment, except that the liner 13^c is shortened axially to be more like one of the baffles 19 and 21 of the embodiment in Fig. 3, and the envelope 12^c is correspondingly shortened so that the lamp is adapted to act substantially as a point-source of light and thereby be suitable for projection and the like purposes.

Although I prefer the use of pure, fused, light-transmitting magnesia for making the intermediate discharge-engaging or restricting portions of the envelope, yet it will be understood that I do not wish to be limited to such material, as pure, fused, light-transmitting alumina or other material having similar qualities, insofar as its endurance to heat and ability to transmit desired radiations is concerned, may be substituted, assuming that it may be formed into the necessary shapes or associated with a quartz or other suitable envelope for a discharge lamp.

From the foregoing description, it will be seen that I have devised an improved lamp particularly adapted for the production of an electric discharge of very much greater intensity than was heretofore possible, radiations of desired character being produced, not only by the discharge, but also by the incandescence of the associated liner, baffle, or baffles of the selected refractory material, which may serve to correct or modify the characteristics of the generated radiations. By virtue of the material selected, the lamp is adapted to efficiently produce and emit infra-red and ultra-violet radiations, as well as visible light.

It will also be understood that, except as here disclosed, such lamps may be constructed like high-intensity discharge lamps in which the envelopes are quartz, that is the processes of exhausting, filling, and other handling during manufacture are similar to those employed in the manufacture of high-intensity mercury discharge lamps having quartz envelopes. Although preferred embodiments of my invention have been disclosed it will be understood that modifications may be made within the spirit and scope of the appended claims.

I claim:

1. An electric discharge lamp comprising an outer envelope formed in part of silicious material and in part of pure, fused, light-transmitting magnesia thicker than the silicious material, a plurality of electrodes therein, and lead-in conductors for said electrodes passing through said silicious material, that portion of the magnesia therebetween serving to direct and/or constrict an arc when formed between said electrodes.
2. An electric discharge lamp comprising a generally cylindrical outer envelope formed of quartz, a pair of electrodes therein, lead-in conductors for said electrodes passing through said quartz, and a plurality of magnesia baffles, corresponding in size with the interior diameter of the envelope and each having a relatively small central aperture, disposed between said electrodes for constricting the discharge therebetween.
3. An electric discharge lamp comprising a relatively short generally cylindrical outer envelope formed of silica, electrodes disposed therein and spaced relatively close to one another, and a baffle of magnesia, corresponding in diameter with the bore of said envelope, provided with a small orifice, and disposed between said electrodes, whereby a discharge therebetween is constricted and a substantially point-source of light obtainable.
4. An electric discharge lamp comprising a generally cylindrical envelope formed in part of silicious material, and in part of a material of higher melting point than said silicious material and selected from the group consisting of pure, fused, light-transmitting materials more refractory than silica, a pair of electrodes therein, lead-in conductors for said electrodes passing through said silicious material, and a plurality of baffles of said higher melting point material, corresponding in size with the interior diameter of the envelope, having relatively small central apertures, and disposed between said electrodes for constricting the discharge therebetween.
5. An electric discharge lamp comprising a relatively short generally cylindrical outer envelope formed in part of silicious material, and in part of a material of higher melting point than said silicious material and selected from the group consisting of pure, fused, light-transmitting materials more refractory than silica, electrodes disposed therein and spaced relatively close to one another, and a baffle of said higher melting point material, corresponding in diameter with the bore of said envelope, provided with an orifice relatively small as compared with said diameter, and disposed between said electrodes, whereby a discharge therebetween is constricted and a substantially point-source of light obtainable.
6. An electric discharge lamp comprising a generally cylindrical outer envelope formed of quartz, a pair of electrodes therein, lead-in conductors for said electrodes passing through said quartz,

and a plurality of alumina baffles, corresponding in size with the interior diameter of the envelope and each having a central aperture relatively small with respect to said diameter, disposed between said electrodes for constricting the discharge therebetween.

7. An electric discharge lamp comprising an outer envelope formed in part of silicious material, and in part of a material of higher melting point than said silicious material and selected from the group consisting of pure, fused, light-transmitting materials more refractory than silica, thicker than the silicious material, a plurality of electrodes therein, and lead-in conductors for said electrodes passing through said silicious material, that portion of the material of higher melting point therebetween serving to direct and/or constrict an arc when formed between said electrodes.

8. An electric discharge lamp comprising an

5

10

15

outer envelope formed in part of silicious material and in part of pure, fused, light-transmitting alumina thicker than the silicious material, a plurality of electrodes therein, and lead-in conductors for said electrodes passing through said silicious material, that portion of the alumina therebetween serving to direct and/or constrict an arc when formed between said electrodes.

9. An electric discharge lamp comprising a relatively short, generally cylindrical outer envelope formed of silica, electrodes disposed therein and spaced relatively close to one another, and a baffle of alumina corresponding in diameter with the bore of said envelope, provided with a small orifice, and disposed between said electrodes, whereby a discharge therebetween is constricted and a substantially point-source of light obtainable.
